CLAIM

The ornamental design for a tent panel, as shown and described.

DESCRIPTION

FIG. 1 is a top, front, right side perspective view of the tent panel;

FIG. 2 is a front view thereof;

FIG. 3 is a rear view thereof;

FIG. 4 is a left side view thereof;

FIG. 5 is a right side elevation view thereof;

FIG. 6 is a top view thereof;

FIG. 7 is a bottom view thereof; and,

FIG. 8 is an environmental perspective view thereof.

(Continued)

In the drawings, the broken lines are for the purpose of illustrating environment only, and form no part of the claimed design.

1 Claim, 6 Drawing Sheets
